(57) **CLAIM**

The ornamental design for a LED light therapy mask, as shown and described.

DESCRIPTION

FIG. 1 is a top, front and right side perspective view of a LED light therapy mask showing my new design;

FIG. 2 is a bottom, rear and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is an enlarged view of the portion labeled “9” in FIG. 1;

FIG. 10 is an enlarged view of the portion labeled “10” in FIG. 4; and,

FIG. 11 is an enlarged view of the portion labeled “11” in FIG. 5.

The broken lines show the portions of the LED light therapy mask that form no part of the claimed design. The dot-dash broken line rectangle frames define the boundary of an enlarged view and form no part of the claimed design.
